(57) **CLAIM**

The ornamental design for a controller housing, as shown and described.

DESCRIPTION

FIG. 1 is a front perspective view of the controller housing.

FIG. 2 is a front view of the controller housing.

FIG. 3 is a right side view of the controller housing.

FIG. 4 is a left side view of the controller housing.

FIG. 5 is a top view of the controller housing.

FIG. 6 is a bottom view of the controller housing; and,

FIG. 7 is a rear view of the controller housing.

The article is a controller housing for electronics.

The broken lines are included for the purpose of illustrating portions of the controller housing that form no part of the claimed design.
